UNITED STATES PATENT OFFICE

121,910

DESIGN FOR A PICTURE PROJECTOR BASE

William Mack, Chicago, Ill., assignor to The
Bell & Howell Company, Chicago, Ill., a cor-
poration of Illinois

Application June 18, 1940, Serial No. 93,075

Term of patent 14 years

To all whom it may concern:

Be it known that I, William Mack, a citizen of the United States, residing at Chicago, in the county of Cook and State of Illinois, have invented a new, original, and ornamental Design for a Picture Projector Base, of which the following is a specification, reference being had to the accompanying drawings, forming a part thereof.

In the said drawings—

Figure 1 is a top plan view of a picture projector base embodying my new design;

Figure 2 is a side elevation;

Figure 3 is a side elevation taken oppositely with respect to Figure 2;

Figure 4 is an end elevation; and

Figure 5 is an end elevation taken oppositely with respect to Figure 4.

I claim:

The ornamental design for a picture projector base, as shown.

WILLIAM MACK.
